UNITED STATES PATENT OFFICE

PAUL SIEBTROTT, OF NEW YORK, N. Y.

BINDER FOR LOOSE SHEETS OR THE LIKE

Application filed December 7, 1928. Serial No. 324,482.

The present invention relates to improvements in binders.

Keeping loose sheets, as for instance newspaper sheets, together and in order is generally annoying and rather difficult especially on trains or subways or the like, where crowded conditions make it extremely difficult to handle such sheets. The sheets tend to slip out of each other or refuse to fold properly and generally succeed in thoroughly exasperating the reader by their contrary behavior.

The principal object of my invention is to provide a simple effective means for temporarily binding such sheets together so that the latter may be easily handled and whereby said means may be removed after use.

Another object is to provide means that can be conveniently carried, in one's pocket-book, pocket, on a chain or a key ring and hence be accessible whenever desired.

A further object is to provide means of such construction as will permit the suspension of said temporarily bound sheets from a wall or other stationary support.

Still another object is to provide a temporary binder which is cheap and easy to manufacture.

With these and many other objects, readily apparent, in view my invention consists in the novel construction and arrangement of a temporary binder, described and shown in the accompanying drawing, in which similar reference characters denote corresponding parts and in which,

Fig. 1 shows in elevation a newspaper, the interleaved sheets of which are held in place by my temporary binder.

Fig. 2 is a top plan view of Fig. 1.

Figs. 3, 4, 5 and 6 show various modifications of my binder.

Fig. 7 is an elevation of the device of Fig. 6 seen in the direction of the arrow showing the method of applying this particular device to loose sheets, and

Figs. 8 and 9 show still other modified forms of my binder.

My binder is preferably made of resilient material, such as phosphor-bronze or steel wire, celluloid or the like and consists essen-

tially of a clamping portion and a suspension portion.

In the embodiment of my device shown in Fig. 3, the binder consists of a member of any suitable material so shaped as to form a loop 10 and a bifurcated stem whose legs 11 and 12 run parallel and very close to one another, the leg 11 being slightly longer than leg 12, and both legs being provided with bent out portions 11' and 12' respectively at their ends. The loop 10 has the double function to wit; one of producing a clamping action between said two legs and two, of serving as means for suspending the binder from any convenient hook rack or other stationary support.

In the device of Fig. 4 the loop 10' is of triangular shape and the leg 12' is indented, corrugated or serrated, as shown to increase the clamping effect and prevent accidental slipping of the sheets held by said leg and leg 11'.

In the modification of Fig. 5 the device is somewhat in the shape of a hair pin and is shaped to form a loop 10' and a bifurcated stem both legs 11' and 12' of which are corrugated, serrated or indented as shown and provided at their free ends with bent out portions 11' and 12'. These legs too are adapted to bear towards each other.

In the modification of Figs. 6 and 7 my binder is formed with a loop 13 and a bifurcated stem having two sets of legs 14 and 15, the legs of set 15 being spaced from each other and those of set 14 lying between the two outer legs 15 and crossing over in the manner shown. A greater clamping action is the result. As before outward bends 14' and 15' are provided to facilitate the insertion of the sheets to be bound.

In the modification of Fig. 8, I show still another form of binder which is formed with a hook 18 and a bifurcated stem having legs 11' and 12' which run parallel and very close to one another, the leg 12' being provided with a bent away portion for the purpose hitherto mentioned.

In the modification of Fig. 9 which is like the modification of Fig. 3 with the exception that it is a double strength clip formed by

doubling each of the sections of the binder of Fig. 3 and which, if made of wire, may be formed by taking a double length thereof, folding it in two and then bending to the 5 shape of Fig. 3. This type of modification can readily be applied to any one of the other modifications shown in much the same way, as is apparent to any one skilled in the art.

In employing my devices, for instance on 10 newspapers, the pages 19 thereof are unfolded along their folds and a fastener slipped on at each end with the legs of the bifurcated sections extending along the fold, and with the loop or hook projecting above the edge of 15 said sheets. The uppermost and lowermost sheets are engaged by said forks or legs and the other sheets are clamped therebetween and all are held firmly and neatly in place. By means of the hook or loop these temporary 20 bound sheets may be suspended from a nail, rod, rack, or other convenient stationary support. When one has finished with the paper the binders may be removed and kept for further use.

25 I need not use these binders only for newspapers but for any other folded or interleaved sheets or the like.

It is obvious that many modifications of 30 my devices may be made without departing from the spirit of my invention and I do not wish to be limited to the details shown and described.

What I claim is:

1. A clip for temporarily binding news- 35 paper sheets in interleaved relationship comprising a forked member of spring material bent to form two opposed arms and further bent over at the folded end to form a suspending hook, said arms being adapted to 40 clamp said sheets together by extending along the fold thereof, one of said arms being straight in its entirety and the second of said arms being shorter than the first and also straight in its entirety except for its 45 free end where it is bent away from said first named arm, said arms being adapted to bear against each other for the full length of the straight portion of the shorter arm and said arms and suspending hook being all 50 arranged in a single plane.

2. A clip for temporarily binding newspaper sheets in interleaved relationship comprising a forked member of spring material 55 bent to form two opposed arms and further bent at the folded end to form a suspending means, said arms being adapted to clamp said sheets together by extending along the fold thereof, one of said arms being straight in 60 its entirety and the second of said arms being shorter than the first and also straight in its entirety except for its free end where it is bent away from said first named arm, said arms being adapted to bear against each 65 other for the full length of the straight por-

tion of the shorter arm and said arms and suspending means being all arranged in a single plane.

In testimony whereof I affix my signature.
